UNITED STATES PATENT OFFICE.

CARLOSTIN BLAKE, OF IDA GROVE, IOWA.

DESIGN FOR A CLOTHES-WASHER.

SPECIFICATION forming part of Design No. 30,575, dated April 18, 1899.

Application filed March 18, 1899. Serial No. 709,688. Term of patent 14 years.

To all whom it may concern:

Be it known that I, CARLOSTIN BLAKE, a citizen of the United States, residing at Ida Grove, in the county of Ida and State of Iowa, 5 have invented and produced a new and original Design for a Clothes-Washer, of which the following is a specification.

This invention relates to a new and original design for a clothes-washer; and it has for its 10 object to provide a design of this character that shall be both useful and ornamental.

The leading feature of the design resides in a hollow conical body provided within the plane of its lower open end with a circular 15 group of conical air-cups of uniform diameter and with a similarly-shaped smaller central air-cup arranged inside of the circular plane of said group of cups and concentric with the latter.

20 The minor features of the design are the hollow conical body provided with a central longitudinal handle-tube extended through and beyond the apex thereof and with a flat horizontal partition registering therein near the lower end thereof.

Additional minor features of the design are the several conical air-cups, having their 25 apices adjoining the horizontal partition and lying flush within the space between said partition and the lower edge of the body, with their contiguous edges, at the flared ends thereof, in proximal relation.

Figure 1 is a perspective view of a clothes-washer embodying the herein-described design. Fig. 2 is a longitudinal sectional view

thereof. Fig. 3 is a bottom plan view of the same.

Referring to the accompanying drawings, the numeral 1 designates a hollow conical body provided with a central longitudinal cylindrical handle-tube 2, extended through and beyond the apex thereof. Said body is further provided with a flat horizontal partition 3, fitting therein near its lower end, and with a circular group of conical air-cups 4, lying 40 flush within the space between said partition and the lower edge of the body. The circular group of conical air-cups 4 are of uniform diameter and directly adjoin the inner peripheral edge of the conical body 1 and also 45 have their apices adjoining the partition 3.

To complete the design, the conical body is further provided with a central conical air-cup 5 of a smaller diameter than the other cups and arranged inside of the circular plane 50 of said other cups and concentric therewith.

All of the air-cups 4 and 5 have their contiguous edges, at the flared ends thereof, arranged in proximal relation.

What is claimed is—

The design for a clothes-washer herein shown and described.

In testimony that I claim the foregoing as my own I have hereto affixed my signature in the presence of two witnesses.

CARLOSTIN BLAKE.
